UNITED STATES PATENT OFFICE.

ITHAMAR DAVISSON, OF LOST CREEK, WEST VIRGINIA.

STOCK-CAR.

SPECIFICATION forming part of Letters Patent No. 595,151, dated December 7, 1897.

Application filed March 16, 1897. Serial No. 627,796. (No model.)

To all whom it may concern:

Be it known that I, ITHAMAR DAVISSON, a citizen of the United States, residing at Lost Creek, in the county of Harrison and State 5 of West Virginia, have invented certain new and useful Improvements in Stock-Cars; and I do hereby declare the following to be a full, clear, and exact description of the invention, such as will enable others skilled in the art to 10 which it appertains to make and use the same.

My invention has relation to improvements in stock-cars, and the object is to provide a car for transporting horses and cattle and which may also be converted into two vertical compartments for sheep, swine, and the like, and to these ends the novelty consists in the construction, combination, and arrangement of the same, as will be hereinafter more fully described, and particularly pointed 20 out in the claim.

In the accompanying drawings the same reference-characters indicate the same parts of the invention.

Figure 1 is a perspective view of my improved stock-car as it appears when used for transporting cattle. Fig. 2 is a perspective view of one of the removable transverse bars 28. Fig. 3 is a transverse section near one end of the car. Fig. 4 is a similar view on 25 the same line, showing the car ready for the large stock. Fig. 5 is a similar view showing the car ready for the small stock. Fig. 6 is a longitudinal section of the car.

1 represents an ordinary stock-car.

35 2 is an auxiliary bottom resting firmly on the usual bottom and of a suitable size to travel freely up and down in the car.

3, 4, 5, and 6 represent a series of converging chains, their lower ends being secured to 40 eyebolts 7, extending through the bottom of the car and fixed in the longitudinal bars 8, fixed to the bottom 2, and their upper ends terminate in a ring connected to a chain 8', the upper end of which is detachably secured 45 to the radial projecting hook 10 on a longitudinal shaft 11, journaled in bearings 13 13, fixed in the ends of the car, and its outer ends project through the ends of the car and through brackets 14 14, terminating in square 50 shanks 15 15, which receive a detachable crank-handle 16, by means of which said shaft

may be rotated to raise and lower the auxiliary bottom 2.

17 represents a pinion fixed on each outer end of the shaft 11, and it meshes with and 55 has a bearing on a similar pinion 18, journaled in the bracket 14 and the contiguous face of the end of the car.

19 represents a pawl pivoted on the outside face of the end of the car, its free end arranged to engage the teeth on the pinion 17 to retain the shaft while being raised, and a second pawl 20 is pivoted on the inner face of the end of the car and also engages a ratchet-wheel 21, fixed on the shaft 11, to assist in holding the shaft while being rotated to raise the bottom 2. This second pawl 20 is provided with a lateral arm 22, which extends through a slot in the end of the car, so that it can be conveniently manipulated by 70 the operator located outside of the car.

The longitudinal shaft 11 is supported within the car by a series of hangers 23, suspended from the carlines 24, and it is centrally divided, its contiguous threaded ends 25 25 engaging the internally-threaded coupling-socket 26 and the lock or jam nuts 27 27, which serve to rigidly secure the ends of said shaft in the coupling. 75

34 34 represent auxiliary chains, their lower 80 ends connected to eyebolts *a* on the bottom 2, and they extend upwardly inside of the car, terminating in a ring 34', connected to a single chain 35', which extends over a grooved pulley 35 and thence along the top of the car, 85 where its inner end is connected to a hook 36 on the longitudinal shaft 11 to support the center of the bottom 2 while it is being raised with the animals.

28 represents one of a series of removable 90 transverse bars provided on their upper faces with rectangular transverse notches 29 29, which receive the longitudinal bars 8 8, and on their opposite sides with similar recesses 30 30, which engage the upper notched edges 95 of the belt-rail 31, so that when in place and the bottom 2 resting upon them the said bars 28 not only support the bottom 2 and the weight on top of it, but by reason of the interlocking recesses just mentioned are as rigidly fixed in place as if they were permanent fixtures. 100

32 represents a flaring guard-rail which extends entirely around the inside of the car to form a protection for the space between the outer edge of the bottom 2 and the sides and ends of the car.

33 33 represent a series of guard-brackets which secure the chain in place after it has been detached from the hooks on the shaft, so as not to be in the way of or in any manner interfere with the animals.

An important feature of my construction is in the fact that swine, sheep, and the like can be loaded on the bottom 2 while it is resting on the bottom of the car and in the same horizontal plane with the usual stationary freight-platform at the station. After the animals are loaded in the car the said bottom 2 may be elevated and secured in place and a second herd loaded in the lower compartment. This saves the expense of building a runway at way-stations to reach up to the middle of the car, as would be necessary if the bottom 2 were first elevated and the animals then loaded in.

While I have specifically described the construction of my invention, I do not desire to be confined to the same, as various modifications will readily suggest themselves to those skilled in the art without departing from the spirit of my invention.

tions will readily suggest themselves to those skilled in the art without departing from the spirit of my invention.

30

Having thus fully described my invention, what I claim as new and useful, and desire to secure by Letters Patent of the United States, is—

A stock-car comprising the vertically-adjustable bottom 2, in combination with the longitudinal shaft 11, provided with the radial hooks 10, the pinions 17 17 fixed thereon, the converging chains 3, 4, 5 and 6, having their lower ends fixed in said bottom 2 and their upper ends secured in a ring 9, a chain 8' having its upper end detachably secured to said radial hook, the pawls 19 and 20, the latter provided with a lateral arm 22, projecting through a slot in the end of the car, and pinions 18 18 fixed on the outer ends of said longitudinal shaft, substantially as shown and described.

35

In testimony whereof I affix my signature in presence of two witnesses.

ITHAMAR DAVISSON.
